UNITED STATES PATENT OFFICE.

ALFRED A. HULL, OF KNOXVILLE, TENNESSEE, ASSIGNOR TO DRAPER CORPORATION,
OF HOPEDALE, MASSACHUSETTS, A CORPORATION OF MAINE.

THREAD-CUTTING LOOM-TEMPLE.

1,241,983.

Specification of Letters Patent.

Patented Oct. 2, 1917.

Application filed April 11, 1917. Serial No. 161,308.

To all whom it may concern:

Be it known that I, ALFRED A. HULL, a citizen of the United States, residing at Knoxville, county of Knox, State of Tennessee, have invented an Improvement in Thread-Cutting Loom-Temples, of which the following description, in connection with the accompanying drawing, is a specification, like characters on the drawing representing 10 like parts.

This invention relates to loom temples provided with thread cutting mechanism and the object of the invention is to provide a device of this character in which the filling 15 shall be severed by a shear cut, in which there shall preferably be two points at which the shear cut shall be made so as to insure the severance of the filling, and in which the blades shall be self-sharpening.

20 The nature and object of the invention will appear more fully from the accompanying description and drawings and will be particularly pointed out in the claims.

In the drawings,
25 Figure 1 is an end elevation of the temple head and adjacent parts;

Fig. 2 is a side elevation partially broken away of the construction shown in Fig. 1;

Fig. 3 is a view in perspective of the preferred form of the fixed member of the cutting instrumentality.

The general construction and operation of 30 thread cutting temples is so familiar to those skilled in the art that only a general description is necessary.

The shank 1 carries at the rearward end 35 the head comprising the pod 2 and cap 3 in which is mounted the rotatable toothed roll 4. Depending from the head of the temple 40 is the heel 5 against which the lay strikes on the beat up to move the temple forwardly in the usual manner.

The pod is slotted at the left hand side, 45 viewing Fig. 1, to provide for the location and operation of the thread cutting instrumentality. This instrumentality comprises a fixed blade and a movable blade the latter being operated by the lay upon the beat up in the usual manner.

50 The fixed blade which is shown in its preferred form separately in Fig. 3 in perspective is a resilient cutting blade of inverted U-shape, one leg 6 of which is rigidly secured in the pod and the other leg 7 of which 55 is pressed by the resiliency of the cutting

blade toward the leg 6. The leg 6 is mounted in a slot 8 formed in the pod so as to support the fixed cutting blade in vertical position and is held in place by a set screw 9.

The movable cutting blade extends longitudinally through the pod, is provided at its forward end with a depending heel 10 and at its rearward end with the hook shaped portion 11, the lower edges 12 of which are the cutting edges. A spring 13 fixed at the upper end at 14 to the temple shank and at the lower end 15 to the heel 10 normally acts to hold the rearward end of the movable cutting blade elevated and projected between the legs 6 and 7 of the fixed cutting blade. Upon the beat up, the lay first comes in contact with the heel 10 of the movable cutting blade and depresses the rearward end of the cutting blade and then swings the cutting blade forwardly drawing the hook end 11 between the legs 6 and 7 of the fixed blade. The inner forward edges of the legs 6 and 7 of the cutting blade are preferably cutting edges although it is only necessary that one should be. So also, both the lower edges of the movable cutting blade are preferably cutting edges although it is only necessary that there should be one to coöperate with the corresponding edge of the fixed cutting blade. The resiliency of the fixed cutting blade by which the leg 7 is pressed toward the leg 6 causes the movable cutting blade to be pinched between the two legs of the fixed cutting blade and a rubbing action thus to take place as the movable cutting blade is operated. The cutting action is a shearing action and if, as preferred, the inner edges of both legs of the fixed cutting blade and both edges of the movable cutting blade are cutting edges this shearing action takes place at two points and the severance of the filling is thus doubly insured. In fact the filling is frequently cut at two points.

Furthermore, the pinching action due to the resiliency of the fixed cutting blade by 100 which these legs are pinched against the movable cutting blade causes a rubbing action which maintains both blades sharpened so that the cutting instrumentality is a self-sharpening one.

The construction as a whole is extremely simple, is readily assembled, and is not liable to get out of order. The action is efficient. The filling instead of being broken or pinched off is cleanly cut by a shearing ac- 110

tion and when both edges are cutting edges there is a double assurance of severance due to the fact that the filling may be cut in either of two or at two points.

5 Having fully described my invention, what I claim as new and desire to secure by Letters Patent is:

1. A thread cutting temple for looms comprising a resilient cutting blade of inverted U-shape secured rigidly by one leg in vertical position in the temple head and having the other leg pressed toward the former leg by the resiliency of the blade, and a forwardly and backwardly movable cutting blade projecting between and contacting with both legs of the rigidly secured blade, whereby a shearing cut is effected upon the forward movement of the movable blade and whereby the cutting edges of the blade are maintained sharp by the rubbing action.

2. A thread cutting temple for looms comprising a resilient cutting blade of inverted U-shape secured rigidly by one leg in vertical position in the temple head, having the other leg pressed toward the former leg by the resiliency of the blade and presenting oppositely disposed inner vertical cutting edges, and a forwardly and backwardly movable cutting blade projecting between and contacting with both legs of the rigidly secured blade and presenting cutting edges at both of its lower edges, whereby a shearing cut is effected at each side upon the forward movement of the movable blade and whereby the cutting edges are maintained sharp by the rubbing action of the blades.

25 In testimony whereof, I have signed my name to this specification.

30 ALFRED A. HULL.
